(57) **CLAIM**

The ornamental design for a dual container assembly, as shown and described.

DESCRIPTION

FIG. 1 is a perspective view of the dual container assembly taken from above, the front and the right side thereof;

FIG. 2 is a front elevational view of the dual container assembly;

FIG. 3 is a rear elevational view of the dual container assembly;

FIG. 4 is a left side elevational view of the dual container assembly;

FIG. 5 is a right side elevational view of the dual container assembly;

FIG. 6 is a top plan view of the dual container assembly;

FIG. 7 is a bottom plan view of the dual container assembly; and,

FIG. 8 is another perspective view thereof that includes a representation of a cover and a retaining member in broken lines.

The broken line showing of the cover and the retaining member in FIG. 8 is for illustrative purposes only and forms no part of the claimed design.
